UNITED STATES PATENT OFFICE.

JOHN H. BROWER AND HERBERT C. ROSS, OF MINNEAPOLIS, MINNESOTA,
ASSIGNORS OF ONE-THIRD TO FRANKLIN L. STILES, OF SAME PLACE.

AUTOMATIC ENVELOPE-FEEDER FOR TYPE-WRITING MACHINES.

SPECIFICATION forming part of Letters Patent No. 476,727, dated June 7, 1892.

Application filed March 28, 1891. Renewed May 6, 1892. Serial No. 432,008. (No model.)

To all whom it may concern:

Be it known that we, JOHN H. BROWER and HERBERT C. ROSS, citizens of the United States, residing at Minneapolis, in the county 5 of Hennepin and State of Minnesota, have invented certain new and useful Improvements in Automatic Envelope-Feeder for Type-Writing Machines; and we do hereby declare the following to be a full, clear, and exact description of the invention, such as will enable others skilled in the art to which it appertains to make and use the same.

Our invention relates to type-writers, and has for its object to provide an automatic envelope-feeder for the same. To this end we 15 employ a magazine adapted to hold a series of envelopes, a follower within the magazine for advancing the entire series of envelopes, and an individual envelope-feeding device 20 adapted to remove the envelopes one at a time from the magazine and supply the same to the type-writer. The magazine, with its feeding devices, is mounted on the feed-carriage of the type-writer, the delivery end of the magazine being in position to discharge the envelope 25 in line with the rear surface of the impression-roller, and the individual envelope-feed device being operated from the line-feed device of the type-writer. The magazine is 30 open at its outer end and the envelope-feed roller is arranged transversely to the line of movement of the follower and is spaced apart from the lower margin or delivery-lip of the magazine the thickness of a single envelope. 35 The follower is provided with an adjustable gage, so as to adapt the same to different sizes of envelopes. The magazine and its feed devices are supported by adjustable holders, so that the same may be set at any angle to the 40 impression-roller or adjusted to different heights to adapt the same to different sizes or arrangements of gearing. The magazine-holders may be sockets for receiving dowel-posts secured to the bottom of the magazine 45 and be provided with set-screws for securing the parts in position. In order to insure the envelopes following the impression-roller to the proper delivery-point, we provide an adjustable guide in the form of a concave which 50 we secure to the front rail of the feed-carriage.

The invention is illustrated in the accompanying drawings, wherein, like letters referring to like parts throughout—

Figure 1 is an end elevation of a type-writ- 55 ing machine known as the "Caligraph" with our invention in working position. Fig. 2 is a front view of the same. Fig. 3 is a cross-section through the envelope-magazine and its feed devices from front to rear, and Fig. 4 is a 60 detail showing the envelope-guide detached.

A represents a part of the body of the type-writer, and B the feed-carriage of the same.

C is the envelope-magazine (shown as of a box-like form) open at its front end and having an inclined bottom. The magazine is provided with dowel-posts D, rigidly secured to its under side. 65

E are the magazine-holders in the form of sockets, mounted on the back rail of the feed- 70 carriage, so as to be adjustable at any angle, and provided with set-screws E' for securing the same on the rail in any desired position. The dowel-posts fit the sockets and are secured therein by thumb-screws E'' or in any 75 other suitable way.

F is the follower within the magazine C having a slot f, in which works the adjustable gage G. The gage is secured in any position in the slot by a set-screw g. The fol- 80 lower is propelled by a spring H, which, as shown, is a flat strip of steel bent upon itself, having its ends secured to the follower near the lower corners of the same and its bent portion or crown bearing against the back of 85 the magazine as a base of resistance. Any other suitable spring might be employed. It is important, however, to locate the spring so that it will have its action on the lower end of the follower; so as to incline the follower 90 slightly backward at its top, thus permitting the outermost of the series of envelopes to be more readily removed without disturbing the others.

K are brackets secured to the outer lower 95 corners of the magazine, which constitute the bearings for the feed-roller L and an idle-gear M. The feed-roller L is preferably made of soft rubber and has a slightly-corrugated surface. It should be so arranged with reference to the delivery-lip of the magazine that 100 the space between the two will be just the

thickness of an envelope, and in order to make the feed reliable the feed-roller must be near the lower outer corner of the magazine, so that its action will be upon the lower margin of the envelope at the start. Otherwise the lower edges of the envelope will turn up around the roller and more than one be fed from the magazine at a time.

The feed-roller L is provided with a gear-wheel l, with which the pinion M is in engagement. The idle-gear M is adapted to engage with the line-feed gear-wheel b on the impression-roller B' of the type-writer feed-carriage. On the Caligraph no change is required to adapt the envelope-feed. On the Remington and similar machines a gear-wheel may be placed on the opposite end of the impression-roller and the idle-gear for communicating the motion to the envelope-feed roller to be also placed on the left side of the magazine for engagement therewith. Otherwise the constructions are alike in both cases.

N is the envelope-guide formed with clamping-jaws n at one end adapted to engage the front rail of the feed-carriage and secured thereon in any desirable position by the clamping-screw N'.

P P', &c., represent a series of envelopes in position within the magazine in front of the follower, of which P is the outermost one of the series.

The operation is obvious. The envelopes are under tension from the spring behind the follower, by which they are pressed constantly at their lower margin against the envelope-feed roller. By operating the line-feed lever of the type-writer, as in the ordinary way for spacing between lines, motion is communicated through the gear M to the feed-roller, turning the same downward against the face of the outermost of the envelopes, thus feeding the same downward into position to be grasped by the impression-roller and operated upon in the ordinary way. When the first envelope has been addressed, the further movement of the line-feed lever will deliver the addressed envelope at the front of the machine over the top of the front rail and bring a second envelope from the magazine into position on the impression-roller to be addressed. The envelope-guide N keeps the envelope in its proper place on the impres-

sion-roller until the work is completed and directs the same to the proper delivery-point over the front guide-rail. The advantage and value of an automatic feed of this character is apparent. More than double the number of envelopes can be addressed on the machine in any given time, and the work will present a more uniform and better appearance.

The device was primarily designed and has been described as an automatic envelope-feed; but it will be understood that it might be used for addressing cards, or even small sheets of paper might be fed in this way to the machine for general writing.

What we claim, and desire to secure by Letters Patent of the United States, is as follows:

1. The combination, with the line-feed devices of a type-writer carriage, comprising the impression-roller, gear-wheel, and actuating-lever, of the envelope-magazine mounted on said carriage, the face-feed roller mounted on said magazine for supplying the envelopes one at a time to said impression-roller and provided with a gear-wheel, and the intermediate gear-wheel carried by said magazine and engaging the gear-wheels of said impression-roller and said face-feed roller for driving the latter from the former, substantially as described.

2. The combination, with the type-writer feed-carriage and its line-feed, comprising the impression-roller, gear-wheel, and actuating-lever, of the angularly and vertically adjustable holders E, mounted on the rear rail of the said carriage, the envelope-magazine C, mounted on said holders, provided with the bearing-brackets K, the follower F, located in the said magazine, the spring H for moving said follower, the face-feed roller L, working against the outermost of the series of envelopes in opposition to the spring H and provided with a gear-wheel l, and the intermediate gear-wheel M, mounted in the said brackets K and engaging the gears b and l, substantially as and for the purpose set forth.

In testimony whereof we affix our signatures in presence of two witnesses.

JOHN H. BROWER.
HERBERT C. ROSS.
